AGITATING MEANS FOR CLEANING FILTERS

Gordon Heatherton Vokes, Guildford, England,
assignor to Vokes Limited, Guildford, EnglandApplication October 11, 1949, Serial No. 120,767
In Great Britain October 18, 1948

3 Claims. (Cl. 183—59)

1

There are well-known filtering installations in which bays or sections of filtering units are agitated and in some cases a reverse flow simultaneously passed through the filtering material to remove accumulated material from the "dirty" side. For example, there is described in German specification No. 441,252 such an arrangement in which air already cleaned by other sections is periodically passed in the reverse direction through a section undergoing cleaning and beaters are simultaneously oscillated inside suitably mounted bags or pockets of filtering material.

The present invention is designed to arrange in an effective manner a balancing action between the beaters in adjacent units, so that excessive vibration is not transmitted to the main framing of the installation.

In a filtering installation of my design slotted or equivalent bars are used to transmit the motion from an oscillating shaft to beaters in the several tiers of fixed units in a bay or section undergoing cleaning. In a simple form of the present invention, cranks transmitting movement to alternate beaters (or very small groups of such beaters) are on opposite sides of a datum line passing through the oscillatory axes of the beaters in their midoperative positions. The sets of beaters in each bag or unit are preferably themselves balanced by one another or by balancing weights, and as the movements and acceleration of the beaters in adjacent bags or groups of bags are alternately clockwise and anti-clockwise, excessive vibration is readily avoided.

The invention is illustrated by the accompanying drawings in which: Fig. 1 is a fragmentary elevation of an installation showing a number of filtering units, and Figure 2 is a fragmentary horizontal section of the installation shown in Figure 1.

Each filtering unit 1 is of the elongated bag type adapted to collect impurities on its outer surface and has a spindle 2 conventionally mounted for oscillation within it. At one end of the spindle, outside the unit, is secured a crank 3 provided with a pin 4 engaged in a slot 5 of a reciprocated bar 6. Pairs of beater members 7 are carried by the spindles 2 within bags of the units 1.

In Figure 1 of the drawings is shown a datum line A—A, and it will be observed that the cranks 3 and pins 4 which are above the datum line have been shown in an operative position, corresponding to a movement of the bar 6 to the right, in which position the corresponding spindles 2 and the beater members 7 connected to them have just completed a clockwise movement.

2

Similarly those cranks and pins 4 which are below the datum line A—A are shown in their extreme right hand position of movement wherein they have just accomplished an anti-clockwise movement which has been transmitted to the corresponding spindles 2 and beater members 7.

It will be apparent that a subsequent movement of the bar 6 to the left, as shown in the drawings, will cause the spindles 2 connected to the cranks 3 above the datum line to perform an anti-clockwise movement, and will cause the spindles 2 connected to the cranks 3 below the datum line to perform a clockwise movement. The beater members 7 carried by the spindles 2 are thus balanced by one another for rotary movement.

I claim:

1. In a filtering installation in which bays or sections of fixed filtering bags or pockets are subjected to balanced pairs of beater members in each bag or pocket, means to oscillate selected balanced pairs of beater members and simultaneously to oscillate other selected balanced pairs of beater members in the opposite directions, the other selected members being mounted in bags or pockets located between bags or pockets wherein the first-mentioned selected members are mounted.

2. In a filtering installation in which sections of filtering units are subjected to agitation, fixed filtering bags, beater members in each bag mounted for balanced rotary oscillation about an axis within the bag, cranks operatively connected to the beaters outside each bag and projecting in equal numbers on opposite sides of a datum line and means to oscillate said cranks simultaneously so arranged that while all the cranks on one side of the datum line cause movement of the attached beater members clockwise all the cranks on the other side of the datum line cause movement of the attached beater members anti-clockwise.

3. Apparatus as in claim 2 wherein the means to oscillate the cranks comprises a reciprocated member engaging all the cranks.

GORDON HEATHERTON VOKES.
